ADJUSTABLE SAW HORSE FOR BENCH SAWS

James A. Crabtree, 391 SW. Forest Drive,
Issaquah, Wash. 98027

Filed Dec. 9, 1974, Ser. No. 531,145

Term of patent 14 years

Int. Cl. D25—99

U.S. CL. D25—67

FIG. 1

FIG. 2

FIG. 1 is a front perspective view of an adjustable saw horse for bench saws embodying my new design.

FIG. 2 is a rear perspective view with the support portion slightly elevated.

I claim:

The ornamental design for an adjustable saw horse for bench saws, substantially as shown.
